UNITED STATES PATENT OFFICE.

JAMES D. TINSLEY, OF NEAR BAKERSFIELD, CALIFORNIA.

ADJUSTABLE SHELVING AND SERVICE DEVICE.

Application filed October 13, 1923. Serial No. 668,292.

To all whom it may concern:

Be it known that I, JAMES D. TINSLEY, residing near Bakersfield, in the county of Kern, State of California, have invented **5** new and useful Improvements in Adjustable Shelving and Service Devices, of which the following is a detailed specification.

This invention relates to shelving for the **10** support and display of merchandise, being particularly adapted for use in connection with merchandise put up in containers such as boxes or cans.

One of the purposes of the invention is **15** to provide a neat, attractive appearing device, partitioned off vertically and horizontally to provide compartments for the various articles to be displayed, and so constructing and arranging the frame-work and partitions that the compartments may be varied in size both as to height and width.

The shelving is sufficiently deep to accommodate a row of articles arranged one behind the other in each compartment, and I **25** have therefore devised means for advancing the entire row, after the foremost article has been removed, so the next succeeding article replaces the article removed. This arrangement is advantageous both from the **30** fact that it presents a pleasing, unbroken display to the view of the prospective purchaser in spite of package removal, and that it obviates the necessity of salesmen having to reach back on the shelves to secure articles originally rearwardly disposed on the shelves.

To accomplish the continual advance of rows, I provide a series of rollers for supporting the articles within each compartment, preferably inclining the members in which the rollers are mounted so the row **35** of articles will roll forwardly when the foremost article is removed. In some cases, the series of rollers may be horizontally arranged from front to back so articles placed thereon will not gravitate towards the front of the device. In such cases, I have arranged means for positively propelling the

articles forwardly. This positive propulsion means may also be taken advantage of **50** in the event the articles are so light or the incline of the rollers so slight that the articles tend to lag in their advance towards the front of the device.

In order that the width of the compartments may be varied by moving the vertical partitions without requiring the substitution of rollers having different lengths for each variation in compartment width, I **55** mount the rollers on the partitions themselves and proportion their length so they extend beneath and support only the ends of the articles (except when occasion arises for reducing the width of certain compartments to the limit by bringing two partitions **60** together until the rollers are in end to end abutting relation). Thus the partitions may be spread apart or brought together without the interchange of rollers, the width of the spaces between the rollers being the **65** only variation caused by the shifting of the partitions.

In connection with the partitions and the mountings of the rollers thereon, I have **70** devised a novel structure which is noteworthy for its simplicity and efficiency. This point will be enlarged upon in the body of the following specification.

I have also incorporated in my device a means for rendering it possible to quickly **75** and easily ascertain the number of articles remaining in each compartment without removing any of the articles. This is a great aid in the taking of inventory and in determining when a new supply of articles should **80** be inserted in any one compartment without waiting until the display front is broken by the unexpected emptying of a compartment.

The shelving may be incorporated with **85** permanently fixed uprights or may be built up in units. In the latter case it is preferable to mount the shelving device on casters so it may be conveniently moved from place to place.

Other objects and features of novelty will

be brought out in the following detailed description, reference being had to the accompanying drawings in which:

Fig. 1 is a front elevation of the device; 5 Fig. 2 is a side elevation of the device; Fig. 3 is a fragmentary vertical section on lines 3—3 of Fig. 1.

Fig. 4 is a fragmentary enlarged horizontal section on line 4—4 of Fig. 1, showing 10 the corner construction of the device.

Fig. 5 is a fragmentary rear elevation of Fig. 3, as viewed from the position of arrow 5.

Fig. 6 is a fragmentary enlarged section 15 on line 6—6 of Fig. 3.

Fig. 7 is a fragmentary perspective of one of the partition and roller units.

Fig. 8 is a fragmentary perspective showing 20 one means for retaining the partitions at given distances apart; the rollers being omitted in this view, and

Fig. 9 is a perspective view of a belt and 25 belt pulley used in connection with the device.

While my invention is capable of adaptation to either permanently fixed supporting structures or to movable supporting units, I will describe only an embodiment of the latter type, although such limitation in the 30 description is not to be construed as limitation of the invention.

The frame work of the device is made up of side frames generally indicated at 10 and 11, each frame comprising front corner post 12 and rear corner post 13 joined by side plates 14, the side frames being maintained in spaced lateral relation by the forward angle irons or cross bars 15 extending between and secured to the front corner posts 12, and rearward angle irons or cross bars 16 extending between and secured to the rear corner post 13, there being a companion angle iron 16 for each forward angle iron 15. Tie rods 17 may be used, if desired, to 40 stiffen the structure. In order to render the unit easily movable, casters 12^a may be mounted on the lower extremities of posts 12 and 13. It is obvious that cross-rods and diagonal bracing between posts 12 and 13 45 may be substituted for plates 14 without departing from the spirit of my invention, but the illustrated construction is preferable in that the side frames are more readily assembled and that the sides of the device are 50 fully closed in to serve as a protection against dust and dirt. An article supporting member generally indicated at 18 extends between each forward angle iron 15 and its companion angle iron 16, the horizontally arranged legs 19 of each angle iron 55 serving as a rest and slide for member 18 and the vertically arranged legs 20 and 20^a of angle irons 15 and 16, respectively, serving as means for limiting the longitudinal 60 movement of member 18. It of course lies

within the spirit of my invention to substitute independent, flatstraps in proper relation, for angles 15 and 16, but the angle irons shown are preferable from a manufacturing standpoint. 70

In Fig. 4 I have illustrated the preferred means for removably attaching angle irons 15 and 16 to corner posts 12 and 13. Horizontal legs or rests 19 of angle irons 15 and 16 are cut away a short distance from the 75 extremities of each angle iron, as indicated at 21, and the tabs 22 thus left at the extremities of each angle iron are bent back at 90° to rest against the inner faces of legs 12 or 13, and punched out at 23 to receive 80 the bolts 24. A series of vertically aligned holes 25 is provided in each corner post, and plates 14 are provided with holes 26 in register with holes 25. Thus, by removing bolts 24, vertically shifting angle irons 15 or 16, 85 and replacing bolts 24, the vertical distance between the forward angle irons 15 or between rearward angles 16 may be varied to accommodate articles of different heights. Preferably, I arrange each rearward angle 90 iron 16 at a higher elevation than its companion iron 15, so that members 18 will incline downwardly and forwardly. Of course the angle of incline may be varied at will by raising or lowering angle irons 16 and utilizing different holes in posts 13 for anchoring bolts 24. Plates 14 are held to posts 12 and 13 by nuts 17^a on tie rods 17, corner post bolts 17^b and angle iron bolts 24. 95

Members 18 are made up of partitions 27, which define the sides of compartments C, roller supporting flanges 28, and rollers 29, these rollers being journaled on shafts 30 which preferably extend through and are supported by partitions 27 and flanges 28. 100 Figures 7 and 8 show a preferred form of article supporting member 18. In forming the member 18 a single sheet of material is first punched at 32 and 33 to provide a series of holes for supporting shaft 31, then bent 105 upon itself at 34 to form central partition 27 each wall 35 of the partition then being bent horizontally to form bases 30, and then bent back parallel to partition 27 to form flanges 28. Partition 27, bases 30, and flanges 28 form a roller receiving channel, in which the rollers are arranged in horizontal alinement, with the tops of the rollers projecting above the upper edges of flanges 28. Bases 30 are adapted to rest on angle 110 iron legs 19, and by sliding the members 18 over legs or rests 19, partitions 27 may be shifted laterally to form compartments of varying widths to accommodate articles of 115 different widths. 120

In order to prevent members 18 from being accidentally slid out of their pre-arranged lateral spacing, I may provide a spacing strip 36, preferably made up of pliable material so that the ends thereof may be 130

bent inwardly at right angles to their body portion, the bent extensions 37 being adapted to be thrust between the walls 35 of the double partition 27. Thus when it is desired to make a change in the width of any one compartment, it is merely necessary to pull out strips 36, shift members 18 laterally to the desired spacing, and rebend strip 36 to suit the new spacing so that ends 37 10 may be again thrust between the walls of the partition. For obvious reasons, such supporting members 18^a as lie adjacent the side frames 10 and 11 are preferably constructed with but one set of rollers and have 15 but a single flange 28.

It will be noted that rollers 29 are relatively short and that the opposed rollers of two adjacent members 18 are adapted to support only the ends of articles in any one compartment. By this arrangement and by reason of the fact that each series of rollers is independently carried by its associated article supported member, the width of the compartments may be varied and the width 25 of articles contained therein varied accordingly, without the necessity of substituting rollers of different lengths. This is obviously of great advantage as a time saving element, for in rearranging the partitions to suit changing conditions of article display it is merely necessary to slide the partition to one side or the other without the necessity of removing or replacing any element of the device (with the exception of spacing strips 36, and in certain cases, these strips may be omitted entirely). It will also be noted that for a given cabinet of shelving, all members 18 are interchangeable, except for those adjacent the side walls of the cabinet, and this 35 is of course a feature of great value from a manufacturing standpoint since material of uniform size and dimension is used throughout, and the amount of forming machinery is reduced to a minimum.

It is evident from the above that articles placed in a row on rollers 29 will gravitate towards the front or forward end of the device so as the foremost article is removed, the next succeeding article will replace it, thus maintaining an unbroken display to the front of the device and placing each article within easy reach as it takes up a foremost position.

In Fig. 7 I have illustrated a means for accurately determining the number of articles remaining in any one compartment without the necessity of removing such articles one by one and counting them and without the necessity of attempting to count the 45 articles by glancing along the tops of the rows. In Fig. 1 I have illustrated only one of such devices, but it will be understood it may be applied to any or all of the compartments. The indicating device is, in effect, 50 an inverted U shaped or channeled measur-

ing stick 38 having a right angled projection or stop 39 at its rearward end.

Indicator 38 is adapted to fit over the top of partition 27 and is longitudinally slidable thereon. Numerals 33^a are painted or applied to the sides of indicator 38 and are arranged in inverse sequence from front to rear, the numerals being spaced apart a distance equal to the width from front to rear of one of the articles carried in the associated compartment. The numeral 1 is of course spaced from stop 39 a distance equal to the width of one such article, and when a compartment is initially filled the indicator 38 is thrust rearwardly until projection 39 75 is flush with the rear of the shelving. Thus, when the compartment is full, projection 39 prevents indicator 38 from being drawn forwardly, due to its contact with the rear-most article, and the numeral exposed at the 80 forward end of the shelving will indicate the number of packages in the compartment. Assuming that a certain number of articles have been removed from a given shelf or compartment, in order to determine how 85 many packages are left it is only necessary for the operator to grasp the forward end of indicator 38 and draw it forwardly until projection 39 contacts with the rear-most package or article, whereupon the numeral 90 exposed to the front of the foremost package is indicative of the number of packages remaining in the compartment.

In some instances rather than depend on gravity, it is desirable to positively propel 100 the articles forwardly after the foremost article is removed. This might occur when a certain member 18 were arranged horizontally rather than at an incline, or when the degree of incline of a member 18 is so slight, or the articles placed thereon are so light as to render the gravitation method ineffectual. For this purpose I journal a pulley 40 in a carrier 41 supported on one of the 105 front angle irons 15 preferably midway between two adjacent partitions 35, mount a spring roller 45 on brackets 43 at the rear of the device, and train a belt or tape 44 from roller 42 about pulley 40, there being a 110 follower 45 attached to the free end of the belt. Follower 45 is made up of base 46 which is of sufficient length to allow its ends to extend and ride upon the opposed rollers in a given compartment, a follower plate 47 115 extending upwardly from base 46, and a hand grip 48 extending to the rear of the plate where it may be grasped for the purpose of manually drawing the follower to the rear of the compartment.

Carrier 41 comprises a base plate 49, brackets 50 in which is journaled pulley shaft 51, vertical clip 52 and horizontal clip 53. The metal making up clips 52 and 53 is preferably somewhat pliable so such clips 120 may be bent into and out of clipping rela- 125

tion with the angle iron 15. Thus, before attachment to the shelving, clip 52 is bent upwardly substantially into the vertical plane of front plate 54, and clip 53 is bent upwardly into substantial parallelism with plate 54 whereupon the carrier is thrust up from beneath angle iron 15 until base 54 and plate 49 are brought into contact with legs 19 and 20, respectively, the clips being then bent into the position shown in Figs. 3 and 9 to hold the carrier to the angle iron 15 and yet allow the carrier to be moved along the angle iron or shifted laterally for the purpose of positioning it centrally of the given compartment. It will be seen that the entire carrier body may be made up from a single sheet of material and the necessary punching and forming operation may be performed thereon with the expenditure of but little labor.

Brackets 43 are provided with clips 55 which are adapted to engage and slide along the vertical legs of angle iron 16, and the rearwardly extending plate 56 which are provided with a plurality of slots or notches 57, the flattened ends of roller shaft 58 being adapted to be non-rotatively held in slots 57. The spring 59 is retained within the cored out center of roller 42 and so attached to the roller and to the roller shaft that with follower 45 in the position shown in Fig. 3 the spring will tend to rotate roller 42 in a counter-clockwise direction to exert a pull on belt 44 and move follower 45 to the left in Fig. 3, or in other words, to draw the follower 45 toward the front of the compartment within which it is contained. By reason of the provision of a plurality of slots 57 in each bracket 43, a single bracket 49 may be used for supporting one end of a plurality of rollers arranged end to end but laterally displaced, thus materially reducing the number of brackets required for a given unit of shelving. It is evident that any two brackets necessary for supporting a single roller may be adjusted towards or away from each other by sliding them along angle irons 16 and thus be made to accommodate rollers of different lengths, and it is also evident that by supplying followers 43 in a number of standard sizes a unit of shelving may be fully equipped with the various follower elements at a very low manufacturing cost.

I provide a series of numerals 60 on belt 44, locating the numerals so that the spacing between them corresponds to the front of rear dimension of a single article within a given compartment, so the operator, by observing the numeral exposed at a predetermined point, say on roller 42, may ascertain how many articles remain unsold within the compartment.

It will be understood that I may make

various changes in structure and arrangement without departing from the spirit and scope of my invention, and therefore I do not wish to be limited to the specific embodiment disclosed except for such limitations as a fair interpretation of the appended claims may impart.

Having described a preferred form of my invention, I claim:

1. An article supporting member for adjustable shelving, embodying an elongated base, vertical flanges along the parallel sides of the base, an upright substantially midway between and paralleling the flanges, and horizontal rollers rotatably supported by and extending between the upright and flanges, the rollers extending above the upper edges of the flanges, and the upright extending vertically above the tops of the rollers to provide a positioning stop for articles supported on the rollers at each side thereof.

2. In adjustable shelving, the combination of side frames, cross bars extending between the frames at front and rear thereof, article supporting members with their ends resting and laterally slidably on the cross bars, each of said members including a series of horizontal rollers and having sockets at their forwardly disposed ends; and spacers extending between and connecting adjacent supporting members to prevent relative lateral movement therebetween, said spacers comprising straps having angularly extending projections adapted to be removably entered in the sockets of adjacent supporting members.

3. In combination, an article supporting member for adjustable shelving, embodying an elongated base, an upright extending longitudinally of the base, horizontally arranged rollers supported by the upright, said upright extending vertically above the tops of the rollers to provide a positioning stop for articles supported on the rollers; and an indicator mounted for longitudinal movement along said upright, the indicator embodying an elongated, inverted channel member whose legs are adapted to straddle the upper edge of the upright, said channel member being adapted to slide longitudinally along the upper edge of the upright and being graduated to agree with the front to rear dimension of a given article on the rollers, and having a projection adapted to be moved into association with the back of the rearmost article on the shelf.

4. An article supporting member for adjustable shelving, embodying an elongated sheet of material bent upwardly along its longitudinal edges to provide vertical flanges, the sheet being bent upon itself between said flanges to provide an upright article positioning stop, horizontal rollers

supported between the upright and flanges, the rollers extending above the flanges, and the upright extending above the rollers.

5. In adjustable shelving, the combination of side frames, cross bars extending between the frames at front and rear thereof, article supporting members with their ends resting and laterally slideable on the cross bars, each of said members embodying an elongated sheet of material bent upwardly along its longitudinal edges to provide vertical flanges, the sheet being bent upon itself between said flanges to provide an upright article positioning stop, horizontal rollers supported between the upright and flanges, 15 the rollers extending above the flanges, and the upright extending above the rollers; and spacers extending between and connecting adjacent supporting members to prevent relative lateral movement therebetween, said spacers comprising straps having angularly extending projections adapted to be removably entered between the walls of the supporting member uprights. 20

JAMES D. TINSLEY.
